UNITED STATES PATENT OFFICE

THOMAS A. McDONNELL, OF LAKEWOOD, OHIO

APPARATUS FOR BENDING ANGLE IRONS

Application filed December 22, 1927. Serial No. 241,953.

The primary object of my invention is to provide a machine for bending various types of metallic bars such as the so called angle iron, to any desired curvature. Inasmuch as the articles fashioned by a machine of this type have a widely varying radius of curvature, it is of essential importance that a machine of this nature be capable of producing work having a wide range of radii. I propose by this invention to provide such a machine that includes a form or mandrel around which the ultimate product is fashioned or bent. This mandrel, while substantially circular in configuration, is susceptible to a wide variation of changes of curvature of its periphery. Clamping means are employed in conjunction with the mandrel for affixing one end of the product in its unfinished state to the form. Bending instrumentalities are also availed of in connection with the mandrel, with which they are relatively movable for bending the work around the form during the stage of shaping the ultimate product.

A noteworthy feature of this invention is the novel mounting of the mandrel together with the bending instrumentalities which permits of either of the last named parts to function as the relatively movable element of the apparatus. This idea is carried out by mounting these parts so that the mandrel may be locked against rotation while the bending means is moved with respect thereto, or if the converse of this condition is desired, the bending means may be held stationary while the mandrel is moved, preferably under power.

Inasmuch as the mandrel is adjustable to varying shapes of the work, the bending instrumentalities provided by this invention are adjustable in their position so that they may at all times be operatively located with respect to the periphery of the mandrel. These last mentioned instrumentalities are further adjustable to accommodate work of various sizes. This object is achieved by including in the structure of the bending instrumentalities, means for adjusting the position of bending rollers included therein.

In order to positively hold bent portions of the work on the mandrel during certain

phases of the shaping of the finished product, I provide clamping means which may be brought into operative position as their use is required. This feature is highly important as it permits of the efficient and accurate operation of the apparatus when work of comparatively large dimensions is being put through the machine.

As previously mentioned, the periphery of the form or mandrel is adjustable as to its radius. Naturally, this entails a circumferential construction thereof which is segmental in character. The actual construction of my apparatus includes blocks mounted on stems or spokes in such a manner that they constitute the portion of the mandrel aforesaid. In their so called extending positions these blocks have a spaced relation as they do in certain positions of their more collapsed state. One of the objects of this invention is to provide a mounting for these mandrel blocks which permits of the removal not only of the blocks from their carrying stems, but also the stems from the remaining structure of the mandrel.

A still further more detailed object of the invention is to provide connecting means between the mandrel blocks that permit of their adjustment in position and yet prevent any rotation thereof. This is of some importance because if the blocks were permitted to turn, the periphery or shaping surface of the mandrel would be materially deformed.

Still another object of the invention is to provide mandrel blocks which include substantially two operating faces, that is, one face of the block may be availed of to accommodate the working when certain types thereof are to be put through the machine, while the blocks may be inverted in their position to afford access to the other surface when a different type of bar is to be shaped. As the bar is operated on by my machine, the structure that is in effect a horizontal flange must be supported during bending operations. This feature assumes some importance when it is considered that it is often desirable to bend the bar either toward or away from the flange aforesaid. When the bar is to be bent away from the flange, a

suitable horizontal supporting surface is provided by the inversion of the mandrel blocks.

In the practical carrying out of the idea in the preceding paragraph, it is necessary to provide clamping means for holding the bars on the mandrel after they are bent when the operation is such that the bars have the outwardly extending horizontal flange. With this in mind, I provide clamping means to cooperate with the clamping means previously described for holding the latter in operative position and which may be availed of when the blocks are used in their so-called inverted position to hold the bent portions of the bars thereon. Under this condition of usage, the first described clamping means cooperate with the last named clamping means to positively hold the same in position.

Further and more detailed object of the invention will in part become apparent and in part be hereinafter stated as the description of the invention proceeds. For a full and complete understanding thereof, reference may be had to the following description and accompanying drawings in which

Figure 1 is a view in side elevation of a bending machine made in accordance with this invention.

Figure 2 is a top plan view somewhat fragmentary of the machine of Figure 1. Dotted lines indicate the position of the mandrel blocks in a collapsed state.

Figure 3 is an enlarged detail illustration taken from the side of one of the mandrel blocks together with a portion of its stem, bringing out the particular construction of the clamping means and mounting of the block, certain positions of the clamping member being indicated by dotted lines.

Figure 4 is an enlarged detail view taken on the line 4-4 of Figure 2 illustrating in particular the connecting means between the mandrel blocks.

Figure 5 is a true cross section taken on the line 5-5 of Figure 1 bringing out the relationship of the mounting of the bending instrumentalities on the main stand when they are held immovable with respect thereto.

Figure 6 is a cross section on the line 6-6 of Figure 1 showing the locking pin in elevation.

Figure 7 is one modification of the shape of the mandrel blocks which may be employed.

Figure 8 is a detailed showing of the mandrel blocks in their inverted position when availed of for the purpose of bending a bar of iron away from its horizontal flange.

While the preferred form of the invention is herein set forth, it is to be understood that I am not to be limited to the exact construction illustrated and described because various modifications of these details may be provided in putting the invention into practice within the purview of the appended claims.

In the present embodiment of the invention, my bending machine is shown as operating in a horizontal plane, but it is to be clearly understood that the machine is well adapted for operation on a horizontal axis, that is, in a vertical plane. The apparatus includes a main support or stand as shown in Figure 1 and designated by the reference character A. The stand may be of any suitable material such as iron or steel and has an upstanding central or hub portion 1 which is hollowed and open at the upper end.

The machine also includes a mandrel designated generally by the reference character B. This mandrel comprises a hub portion 2 of considerable longitudinal extent and adapted to be received within the hollow hub portion 1 of the stand A. Intermediate the ends of the hub 2 and connected therewith in appropriate fashion as by the flange structure 3, extend spokes 4. At their outer extremities, the spokes 4 are connected together by the ring member 5. The ring 5, spokes 4, flange structure 3, and hub 2, together with a driving gear 6 constitute the main body portion 90 of the mandrel.

A gear 7 on one end of a driving shaft 8, which is in operative engagement through the medium of bevel gears 9 with a motor 10, causes rotation of the mandrel. While the driving means is shown as a motor, this element is subject to a wide range of variation inasmuch as any prime mover capable of causing proper rotation of the mandrel B for the functioning of the machine, may be availed of. The driving shaft 8 may have suitable support in the form of a bracket 11.

The spokes 4 are provided with threaded bores as shown at 12. These bores extend through the ring 5 and are adapted to receive the threaded shanks of stems 13. Between the points of connection of the spokes 4 with the ring 5, the last named part is provided with threaded openings 14 which are also adapted to receive certain of these stems 13. If it is found desirable, the ring 5 may be provided on its inner circumferential surface with extensions or bosses 15 for providing sufficient engagement between the stems 13 and the ring 5 to properly mount the stems therein. Each of the threaded shanks of the stems 13 is provided with a lock nut 16 for positively holding the stem in proper relation with respect to the ring 5.

Referring now more particularly to Figure 3, the stems 13 at their outer ends have a squared portion 17 that provides a wrench engaging surface by which the stems 13 may be rotated by an appropriate tool for the purpose of adjusting the position of the blocks. It is notable that in order to screw the stems 13 in and out of the bores receiving them in the ring 5, it is first necessary to loosen nuts 16 so as to permit of this adjustment. Adjacent their outer extremities the

stems 13 are also provided with grooves 18 for a purpose to be hereinafter more fully set out.

Blocks 19 are detachably mounted on each of the stems 13 at their outer extremities. The blocks 19 are provided on their inner faces with coupling members 20 having bores 21 which receive the ends of the stems 13. These coupling members are affixed to the block in any approved manner, as by screws. Set screws 22 are threaded in suitable openings in the coupling members 20 so that their ends project into the bores 21 when they are threaded in sufficiently far. In fastening the blocks to the stems, the screws 22 are unscrewed so as to leave unrestricted bores in the couplings 20, whereupon the ends of the stems 13 are inserted in the bores so that grooves 18 are in substantial alignment with screws 22. These screws may then be threaded on either sufficiently far to prevent disengagement from the blocks 19 from the stems 13, still permitting of their rotation, or down tight whereby all relative movement between the blocks and stems is prevented. It will be apparent that the connecting structure just described affords a coupling between the parts that permits any one of the stems 13 to be rotated without entailing a corresponding rotation of the block 19 which it carries. This also allows for the detaching of the blocks from their respective stems. The outer circumferential faces of the blocks are curved on a suitable arc to provide in effect a mandrel 35 having a large adjustable radius.

As previously mentioned, one of the important features of the invention is the adjustability of the mandrel blocks to provide a form of varying radius. In carrying out this idea, spaces between the blocks 19 must necessarily exist when the mandrel is adjusted to have a comparatively large radius. The space between these blocks permits the radius of the mandrel to be diminished to the point where the circumference will have become so small that the blocks abut one another. If it is desired to operate the machine to produce work the curvature of which has a still smaller radius, the machine may be adapted for such use by removing each of the stems 13 that are threaded in the openings 14. This in effect is the removal of every other one of the mandrel blocks 19. The remaining blocks may be collapsed to a further extent by screwing the remaining stems 13 into the bores of the spokes 4. This inward radial movement may be carried on until the mandrel blocks still in the structure, again abut one another. This construction permits the periphery of the mandrel to assume any radius within a wide range.

To maintain the blocks 19 in proper alignment during all stages of operation and adjustment of the mandrel, I have provided connecting means between these blocks which

consists of linked members 23 having slots 24 therein. Each of the links 23 is positively secured at one end to one of the blocks 19 in any approved manner, as by screws 25. The other end of each of the linked members 23 is fastened to an adjacent block by suitable headed elements such as screws 25 passing through the slots 24. This permits of relative movement between each of the blocks connected by one of the linked members 23 and yet prevents any rotation thereof. When the mandrel is collapsed to such an extent that the removal of alternate mandrel blocks is necessitated, the linked members 25 may be detached from the blocks by removal of the screws 25. One of the mandrel blocks 19, preferably one in alignment with a spoke 4, is provided with an abutment member 26 against which one end of the bar or angle iron to be bent by the machine, is placed.

Each of the blocks 19 is cut away on one side as shown at 26^a to provide an angular groove around the outer periphery of the mandrel. This cut-away groove may be availed of when the machine is to bend work 90 having an outwardly extending flange. The relationship of the angular iron to the machine under this condition is clearly brought out in Figure 8. On the unbroken plane surface of the block a clamp member 27 is pivoted to the block by a pin 28. The clamp 27 comprises an angular portion 29 pivotally connected to the swinging portion 30 of the clamp. The angular portion 29 is of proper dimensions to substantially encompass any angle irons that are to be operated on by the machine. When the clamps are not to be availed of, they may be swung out of the way in the manner clearly brought out by the dotted line positions of Figure 3. The cut-away face of the block is provided with a second clamp 31 which is pivoted to the block at 32 in a suitable recess. A spring clip 33 may be added to the structure of the block in the position indicated in Figure 3. The clamps 27 and 31 are provided with small openings in their free ends which are arranged so that they overlap when the clamps are in operative position. A pin (not shown) may be passed through these openings to prevent relative movement of the clamps and thereby hold the same in clamping position.

Now coming to the bending instrumentalities; these parts comprise collars 34 and 35 together with a yoke member 36 and turnbuckle couplings 37. The collar 35 surrounds the hub 1 of the stand A and is provided with openings 38, any one of which may be brought into alignment with a recess 39 in the hub 1. A pin 40 may be inserted in the recess 39 and the opening 38 aligned therewith to prevent relative rotation between the bending instrumentalities and the stand. A threaded shank 41 extends from the collar 35 and is connected

with the yoke member 36 by turn-buckle 37. The collar 34 encircles the hub 2 of the mandrel, and is adapted to rotate with respect thereto. This collar has a threaded arm 42 by which it is connected with the yoke 36 through the medium of a turn buckle 37.

The yoke 36 has mounted in slots therein a bolt 43 which is constantly urged toward the mandrel by coiled springs 44. The bolt 43 carries a bending roller 45 which projects to the cut-away portion 26 of the mandrel blocks when they are inverted to bear against the vertical flange of the work as they do when the blocks are in their normal position as shown in Figure 1. Yoke 36 also carries a roller 46 in a somewhat retarded position with respect to roller 45. The roller 46 bears against the horizontal flange of the work in rigidly holding the same against the flange supporting surface of the mandrel blocks. The position of the roller 46 may be varied by proper adjustment of its mounting on the yoke member as shown at 47.

When it is desired to hold the mandrel against rotation, a pin 48 may be passed through the proper openings 49 in the hub 1 that are in alignment with the hole 50 in the hub 2. When the machine is to be operated under this condition, motion may be imparted to the bending means by inserting a handle 51 in an opening 52 in the yoke member 36 to afford ample leverage to perform the bending operation.

The operation of the bending machine is substantially as follows:—

The mandrel is adjusted to the proper radius by turning the stems 13 and the desired surface of the mandrel blocks are brought into their upper or operative positions. Work in the form of an angle iron 53 is fed to the machine by placing one end thereof against the abutment 26 and the clamp adjacent thereto is placed in. If the work is fairly heavy, the preferred form of operation is to hold the bending instrumentalities stationary while the mandrel is rotated under power. Power is then applied to cause rotation of the mandrel, whereby the angle iron is bent around the mandrel as the rollers 45 and 46 positively hold the angle iron against the mandrel blocks. If, for any reason, the pressure on the roller 45 should become so great that damage to the machine is likely to be incurred, the springs 44 permit the roller 45 to give to a certain extent. As the angle iron passes from the rollers 45 and 46, the clamps may be brought into operative position as the occasion demands. When the work is to be taken from the machine, the clamps may be swung out of their operative position, and the angle iron readily removed. If the iron is to be bent away from its horizontal flange, the mandrel blocks are inverted to bring the cut-away face into operative position, where-

upon the machine may be operated in the manner aforesaid.

It will be apparent from the foregoing that I have provided a machine which is capable of bending bars having flanges in either direction and which is capable of adjustment to afford a wide range in the curvature of the ultimate product.

Having thus described my invention, what I claim as new and desire to secure by Letters Patent of the United States is:—

1. A machine of the class described, comprising, in combination, a circular form or mandrel consisting of radially movable sections, means for adjusting the size of the mandrel, bending instrumentalities, means for adjusting the bending instrumentalities to the size of the mandrel, and means for causing relative movement between the mandrel and the bending instrumentalities.

2. A machine of the class described, comprising, in combination, a circular form adapted to have an angle iron bent there-around, said form consisting of radially movable sections, bending instrumentalities including rollers adapted to engage the work being bent by the machine, and means for adjusting the position of the rollers to the size of the form.

3. A machine of the class described, comprising, in combination, a circular mandrel adjustable as to its radius, means for fastening one end of an angle bar to the mandrel, means for causing rotation of the mandrel, bending instrumentalities, and means for clamping the work to the mandrel after it has passed through the bending instrumentalities.

4. A machine of the class described, comprising, a circular mandrel, and instrumentalities for bending angle irons around the mandrel, the said mandrel being sectional in construction and including means for adjusting the positions of the sections radially of the mandrel axis whereby the size of the mandrel may be varied, as desired.

5. A machine of the class described, comprising, in combination, a support, an adjustable mandrel rotatably mounted on the support, bending instrumentalities immovably mounted with respect to the support, means for rotating the mandrel, and means for clamping an angle iron to the mandrel after it has passed through the bending instrumentalities.

6. A mandrel of the class described, comprising a hub portion, spokes, and a ring member connected to the hub portion by the spokes, stems mounted in the ring member, and mandrel blocks carried by the stems, said stems being adjustable to adjust the positions of the mandrel blocks whereby the size of the mandrel may be varied as desired.

7. A mandrel of the class described, comprising, a hub portion, stems mounted in the

hub portion, mandrel blocks rotatably mounted on the stems, means for preventing relative movement between adjacent mandrel blocks, and means for adjusting the stems whereby the mandrel blocks may be adjusted to provide varying sizes of the mandrel.

8. A mandrel of the class described, comprising a hub member, stems extending from the hub member, mandrel blocks on the stems, the mandrel blocks having angularly disposed operating faces, and means to bring each of the faces of the blocks selectively into operative position.

9. A mandrel of the class described, comprising, in combination, a hub, stems extending from the hub, mandrel blocks rotatably mounted on the stems, means for adjusting the relative position of the blocks to vary the effective size of the mandrel, and means connecting the mandrel blocks whereby rotation of the latter is prevented, during adjustment of the mandrel blocks.

10. A mandrel of the class described, comprising, a hub, spokes, a ring connected to the hub by the spokes, stems adjustably mounted in the ring, mandrel blocks carried by the stems, and means for connecting the mandrel blocks together, whereby rotation of the latter is prevented while the position of the same is being varied by adjustment of the stems.

11. A machine of the class described, comprising, in combination, a support, a sectional mandrel rotatably mounted on the support, means for adjusting the sections of the mandrel to vary the size of the latter, bending instrumentalities associated with the mandrel, means for adjusting the position of the bending instrumentalities to the size of the mandrel, and means for clamping work to the mandrel after it has passed through the bending instrumentalities.

12. A machine of the class described, comprising, in combination, a support, a sectional mandrel mounted for rotation on the support, means for adjusting the sections of the mandrel to provide varying sizes of the latter, bending instrumentalities associated with the mandrel, including rollers, means to adjust the bending rollers to the sizes of the mandrel, means for clamping work after it has passed the rollers to the mandrel, and means for causing relative movement between the mandrel and bending instrumentalities.

55 In testimony whereof I affix my signature.

THOMAS A. McDONNELL.
